ABSTRACT: The disclosure describes an over-the-shoulder garment carrier comprising a garment bag, a flexible handle comprising an elongated loop and an end portion or linking piece which is secured to said garment bag, the flexible handle carrying a first loop adapted for carrying the hook end portion of a conventional suit hanger, such that the weight of the garments are supported primarily by the first loop rather than by the end portion of the flexible handle, said flexible handle additionally carrying a lock strap, said lock strap having a first end portion secured to the flexible handle at a point between the first loop and the garment bag such that the lock strap, when formed into a second loop, extends generally at a right angle to the longitudinal dimension of the flexible handle whereby the second loop prevents the hook end portion of a conventional suit hanger, which inadvertently has become detached from the first loop, from slipping into the garment bag.

OVER-THE-SHOULDER GARMENT CARRIER

BACKGROUND OF THE INVENTION

The present invention relates to an over-the-shoulder garment carrier. More particularly, the present invention relates to an over-the-shoulder garment carrier having means to appropriately distribute load and to prevent hanger slippage.

Many types of garment carriers are known in the art. Galazin U. S. Pat. No. 3,362,599 describes an over-the-shoulder garment carrier which has an elongated strap for supporting such a carrier. The carrier in Galazin describes multiple slots or loops for carrying garment hangers, which slots or loops act to distribute the weight longitudinally along the base of the carrier. The present invention, on the other hand, provides an over-the-shoulder garment carrier having means for carrying the weight of the garments such that tension on the linking piece which connects the handle portion to the garment bag is substantially reduced thereby extending the life of the garment carrier. The present invention also contemplates an over-the-shoulder garment carrier having means for preventing inadvertently detached garment hangers from slipping into the garment bag.

Other aspects and advantages of the invention will be apparent from the accompanying drawings and description.

SUMMARY OF THE INVENTION

The present invention relates to an over-the-shoulder garment carrier comprising:

- A. a garment bag;
- B. a flexible handle comprising an elongated loop and a linking piece, the linking piece being secured to the garment bag;
- C. the flexible handle carrying a first loop adapted for carrying the hook end portion of a conventional suit hanger such that the weight of the garments is supported primarily by the first loop rather than by the linking piece;
- D. the flexible handle additionally carrying a lock strap, the strap having a first end portion secured to the flexible handle at a point between the first loop and the garment bag such that the lock strap, when formed into a second loop, extends generally at a right angle to the longitudinal dimension of the flexible handle whereby the second loop prevents the hook end portion of a conventional suit hanger, which has inadvertently become detached from the first loop, from slipping into the garment bag.

BRIEF DESCRIPTION OF THE DRAWINGS

FIG. 1 is a front view, in elevation, of the preferred embodiment.

FIG. 2 is a side view, in elevation, and partially in section, of the preferred embodiment.

FIG. 3 is a sectional view taken at line 3—3 of FIG. 1.

DESCRIPTION OF THE PREFERRED EMBODIMENT

FIG. 1 describes a garment carrier 10 comprising a garment bag 11 adapted for storage of suits, coats, etc. which are carried by a conventional garment hanger, the hook portion of which is shown at 18. Access to the inside of the garment bag 11 is provided by zipper opening means 12.

Referring now to FIG. 2, the carrying strap for garment carrier 10 is generally denoted by the numeral 14 and comprises a single elongated, reinforced piece of flexible material folded upon itself and secured by stitching 24 in such a way as to form a carrying loop 15 and a smaller garment hanger loop 16. The end portion or linking piece 21 of carrying strap 14 is attached in any convenient manner to the upper end portion of garment bag 11, preferably by stitching.

Carrying loop 15 is adapted for carrying garment bag 11 in an over-the-shoulder mode. The garment hanger loop 16 provides the loop from which the hook ends of garment hangers 18 are hung. The carrying strap 14 is designed such that the weight of the garments is primarily carried by hanger loop 16 rather than by linking piece 21. Thus, the point of attachment of handle end portion or linking piece 21 to garment bag 11 is

relieved of tension that would otherwise be caused by the weight of the garments thereby preventing ripping or tearing of the garment carrier linking piece at the critical juncture.

Referring now to FIG. 3, a hanger lock strap 20 is permanently attached to one end thereof to carrying strap 14 at a point between the lower edge of hanger loop 16 and the garment bag 11. Lock strap 20 is designed to be removably fastened upon itself for quick detachability and attachability by any convenient means, such as the snap fastening means shown at 25, so as to form a closed loop which prevents inadvertently detached hangers from slipping into the garment bag 11.

Garment bag 11 may be made of any suitable material such as leather, vinyl, thermoplastic, etc. Similarly, carrying strap 14 may be made of the same kinds of materials and may be reinforced with other materials such as nylon webbing, etc., to increase its strength and wearability. Finally, the hanger lock strap 20 may be detachably fastened by other convenient means such as, for example, buckle fastening means.

I claim:

1. An over-the-shoulder garment carrier comprising
  - A. a garment bag;
  - B. a flexible handle comprising an elongated loop and a linking piece, said linking piece being secured to said garment bag;
  - C. said flexible handle carrying a first loop adapted for carrying the hook end portion of a conventional suit hanger such that the weight of the garments is supported primarily by said first loop rather than by said linking piece;
  - D. said flexible handle additionally carrying a lock strap, said strap having a first end portion secured to said flexible handle at a point between said first loop and said garment bag such that the lock strap, when formed into a second loop, extends generally at a right angle to the longitudinal dimension of said flexible handle whereby said second loop prevents the hook end portion of a conventional suit hanger, which inadvertently has become detached from said first loop, from slipping into said garment bag.
2. An article of manufacture as in claim 1, wherein the lock strap has a second end portion adapted to be removably fastened to said first end portion.
3. An article of manufacture as in claim 1 wherein said flexible handle and said first loop are formed from one continuous, elongated member.
4. An over-the-shoulder garment carrier comprising
  - A. a garment bag;
  - B. a flexible handle comprising an elongated strap having a first end portion secured to said garment bag, the remaining portion of said strap folding back upon itself so as to form a major loop and a minor loop, said major loop adapted to be carried over the shoulder and said minor loop adapted for carrying the hook end portion of a conventional suit hanger such that the weight of the garments is supported primarily by said minor loop rather than by said end portion of said flexible handle;
  - c. said flexible handle additionally carrying a lock strap, said lock strap having one end portion secured to said flexible handle at a point between the leading edge of said minor loop and the point of attachment of said garment bag to said flexible handle, and a second end portion such that when said second end portion is attached to said first end portion, a second loop is formed, said second loop extending generally at a right angle to the longitudinal dimension of said flexible handle, whereby said second loop prevents the hook end portion of a conventional suit hanger from slipping into said garment bag if said hook end becomes detached from said first loop.
5. An article of manufacture as in claim 1 wherein the second end portion of the lock strap is fastened by snap-fastening means.
6. An article of manufacture as in claim 4 wherein the second end portion of the lock strap adapted to be removably fastened to the first end portion of the lock strap is fastened by buckle-fastening means.

UNITED STATES PATENT OFFICE
CERTIFICATE OF CORRECTION

Patent No. 3,612,260

Dated October 12, 1971

Inventor(s) Robert A. Brilhart

It is certified that error appears in the above-identified patent and that said Letters Patent are hereby corrected as shown below:

Column 2, line 63, after "portion" insert --adapted to
be removably fastened to said first end portion--

Column 2, line 72, after "strap" insert --adapted to be
removably fastened to said first end portion--.

Signed and sealed this 28th day of March 1972.
